UNITED STATES PATENT OFFICE.

ROGER S. WHITE, OF WASHINGTON, DISTRICT OF COLUMBIA.

METER-SWITCH.

1,228,859.

Specification of Letters Patent.

Patented June 5, 1917.

Application filed August 22, 1916. Serial No. 116,295.

To all whom it may concern:

Be it known that I, ROGER S. WHITE, a citizen of the United States, residing at Washington, in the District of Columbia, have invented certain new and useful Improvements in Meter-Switches, of which the following is a specification.

This invention relates to a switching device adapted for use particularly on meter test blocks. The invention comprises a suitable base of insulating material, a switch terminal secured upon the front of the base, and a co-operating switch terminal comprising a threaded stud projecting from the base beyond the first mentioned terminal and a threaded contact member adjustable on the stud into and out of engagement with the first mentioned terminal, said co-acting switch member having means, in front of the base, for detachably connecting a meter test wire thereto. The means for detachably connecting the meter test wire preferably comprises an opening or recess into which the wire may be hooked, and this opening may be either in the stud or in the member, adjustable thereon, the former arrangement being preferred, and the said adjustable member then becomes a locking means for the wire. It will be understood that several switching devices are required to make the necessary circuit changes to apply a test meter, but as these devices may be all alike, it is unnecessary to illustrate or describe the entire set of switches.

35 In the accompanying drawing, which illustrates my invention,

Figure 1 is a front or plan view of a switch block having thereon a pair of switches embodying my invention;

40 Fig. 2 is a section on the line 2—2 of Fig. 1;

Fig. 3 is a section on the line 3—3 of Fig. 1;

45 Fig. 4 is a plan view of a modified form of switch; and,

Fig. 5 is a section on the line 5—5 of Fig. 4.

Referring to Figs. 1 to 3, inclusive, of the drawing, A indicates a base of insulating material upon which two similar switches a and b are mounted. Each switch comprises a flat metal strip or plate 1, lying flat on the base and secured thereto by a binding screw 2, which engages a threaded opening 3 in the plate, and also extends through an opening in the base. A lock nut 4 at the front of

the plate prevents the screw from turning, and the part of the screw at the rear of the base is provided with clamping nuts, 5, 6, the former for holding the plate firmly against the base, and the latter for securing the terminal of a conductor 7 to the binding screw.

The opposite end of the metal strip 1 is provided with a circular opening 8, tapering from the base outwardly, as shown, and a threaded metal stud 9 extends through said opening and through an opening in the base. This stud is provided with a conical shoulder 9^a, which fits against the base, and a conical washer 10, of insulating material, fits 76 into the opening 8 between said shoulder and the plate 1. The stud is held in fixed position by a nut 11 thereon, at the back of the base, and the terminal of a conductor 12 is secured on the stud by a nut 13.

The stud 9 projects in front of the base and of the plate 1 for a suitable length to support a metal contact member 14, which is in the form of a nut threaded on to the stud and which is movable into and out of engagement with the plate 1. The plate 1 forms one terminal of the switch and the stud and nut form the other switch terminal. When the nut is screwed inwardly against the plate, as shown at the right in Fig. 2, the switch is closed, and the conductors 7 and 12 are electrically connected together. When the nut is unscrewed, as shown at the left in Fig. 2, the electrical connection between the conductors 7 and 12 is interrupted.

The stud of each switch is provided with means for detachably connecting one of the wires of a test meter thereto. In this instance, holes 15 are bored through the studs, near their outer ends, to receive the test meter wires, one of which is shown at 16, which wires are usually bent into hook form at their ends and hooked into the perforations. The perforation in each stud forms a satisfactory means for connecting a test wire to the stud, but in order to secure the wire against accidental displacement, the nut 14 may be adjusted outwardly on the stud until its outer face bears against the wire, as indicated in Fig. 3, and the nut then locks the wire against displacement. Thus, the nut 14 plays between the opening 15 and the terminal 1 and performs the mechanical function of clamping the test wire when in its outer position, and the electrical function of connecting the conductors 7 and 12 when in its innermost position. As the exposed

end of the stud projects a considerable distance from the opposing terminal 1, ample room is provided for connecting the test wire to the stud without bringing the wire 5 close to the terminal 1. There is, therefore, little or no danger of short circuiting the switch in handling the meter test wire.

In the switching device above described, the metal surfaces of the nut and stud where 10 they project forward or in front of the base are uninsulated and wholly exposed, so that the meter test wire might be attached to either the nut or the stud, if a suitable perforation were provided in the former. In 15 Figs. 4 and 5, a switch is shown in which the nut is perforated to receive the test wire.

In Figs. 4 and 5, the parts are the same as in Figs. 1 to 3, inclusive, with the exception of the stud and nut. Referring to these 20 latter figures of the drawing, the stud 9^b is not perforated, and the nut or sleeve 14^b extends beyond the end of the stud in the closed position of the switch. The nut, near its outer end, is provided with a perforation 25 15^b, extending diametrically through it, for receiving the hooked end of a meter test wire, and a slot 17 is formed in the end of the nut or sleeve so that a screw-driver may be inserted to tighten or loosen it. When 30 the switch is opened by unscrewing the nut, the meter test wire may be inserted through the perforation 15^b, and then by screwing the nut downward, the wire will be clamped against the end of the stud.

35 In both forms of switch, a single turn of the nut will open or close the switch; but the stud is long and threaded to its outer end, so that many turns of the nut would be required to remove it from the stud. It is intended that the nut shall remain on the stud 40 at all times, and with this arrangement the operator is not likely to unscrew the nut so

far that it will drop off, which occurrence might cause a short circuit at some other part of the test block. As the test blocks for 45 which these switches are adapted are intended to be placed within small spaces in the meter casings, it is important to guard against such accidental displacements of 50 metal parts.

What I claim is:

1. In a switch for meter test blocks, a suitable base, a switch terminal supported thereby, and a co-acting switch terminal comprising a threaded stud projecting from the base outwardly beyond the first mentioned terminal and a threaded contact member on said stud, said co-acting terminal having, in front of the first mentioned terminal, means for detachably connecting a meter wire thereto.

2. In a switch for meter test blocks, a suitable base, a switch terminal supported thereby, and a co-acting switch terminal comprising a threaded stud projecting from the base outwardly beyond the first mentioned terminal and a threaded contact member on said stud, said co-acting terminal having, in front of the first mentioned terminal, a perforation to receive a meter test wire.

3. In a switch for meter test blocks, a suitable base, a switch terminal supported thereby, and a co-acting switch terminal comprising a threaded stud projecting from the base outwardly beyond the first mentioned terminal and having means in front of said latter terminal for the attachment of a wire and a threaded contact member on the stud, said member adjustable into locking engagement with the wire, when the latter is attached.

In testimony whereof I have affixed my signature.

ROGER S. WHITE.
